UNITED STATES PATENT OFFICE.

FRIEDRICH MERK, OF MUNICH, GERMANY.

DESK TELEPHONE STATION.

Application filed January 29, 1925, Serial No. 5,586, and in Switzerland December 15, 1924.

This invention has for its object to create a desk telephone station with hand set and finger dial which is of compact, simple and cheap construction.

5 The invention relates especially to the shape of the casing and to the special arrangement of the finger dial and of the hand set.

The casing of the apparatus composed of 10 a pedestal and of a box is, as regards shape and size, adapted to the finger dial embedded in the inclined top plate of the box and it is fitted with a fork-shaped support for the hand set arranged so that the hand set viewed 15 from above in the position of rest intersects the casing.

As the finger dial is mounted on the top side instead of the front side of the casing it is possible to give a low height to the apparatus. The inclined position of the finger dial which facilitates the manipulation of the same does not change anything with regard to the advantage stated. As the finger dial is embedded in the box and not mounted 20 on the same no special frame for the finger dial is required and the casing is of smooth outlines. The adaption of the casing of the desk telephone station, as regards shape and size, to the finger dial permits of reducing 25 the size of the station and reduces the cost of manufacture owing to the saving of material. To obtain these advantages the construction of the apparatus must be carefully considered and they must be cleverly 30 accommodated in the casing, and the fork-shaped support for the hand set must also be cleverly arranged so that the supporting points for the hand set are situated above the finger dial. Any suitable construction 35 and mounting of the fork-shaped support may be used. The hand set is arranged a short distance above the finger dial in order that the weight of the hand set acts as closely as possible to the centre of the station so that 40 the stability of the desk telephone station is increased. This arrangement presents further the advantage that the user of the station must remove the hand set from the fork-shaped support before he can adjust 45 the finger dial on the desired number.

For the purposes of the invention a small finger dial is especially adapted, as to such a finger dial corresponds, in accordance with the invention, a small, round or rounded casing, which can be simply and inexpensively 50 made from sheet metal, offers large inner

space for its height if properly selected, requires little material and harmonizes well with the inner finger dial. According to the invention the casing is arranged so that the finger dial can be mounted on the same in inclined position, and the finger dial can be built in later on, e. g. when the central exchange has been arranged for full automatic service.

An embodiment of the invention is illustrated, by way of example, on the accompanying drawing, in which:

Fig. 1 is a front elevation of the improved desk telephone station.

Fig. 2 is a plan view of the same.

Fig. 3 is a side elevation of the desk station, the casing being shown in section.

Fig. 4 is a plan view, the top part of the box being removed.

The casing of the apparatus consists of a box D of circular cross section and of a circular pedestal S. The top plate of the box is forwardly inclined and has an aperture into which a number switch N, with finger dial 80 of small diameter and having finger holes arranged in a circle in a manner known per se, is inserted. A two-armed fork-shaped support G for the hand set M is further arranged on the top plate of the box. To make 85 room for this support the number switch is displaced forwards from the center of the box. This displacement is so slight that the number switch covers nevertheless the main part of the top plate of the box, the diameter of this top plate being only slightly greater than the diameter of the number disk. The horizontal axle A for the support G is mounted in two round holes arranged in side walls 90 of a bulged out part of the rear upper end of box D. The upwardly directed and slightly forwardly inclined two arms of the support G, fork-shaped at the upper ends, are fixed on the two projecting ends of axle A. The axle G with the arms of the support is adapted to rotate between two stops. When the micro-telephone M is taken off the support G, the support is pulled away from the finger dial by the action of a spring and when it is placed on the support this support is lowered towards this finger dial. This movement of the support is utilized for 95 controlling the switch contacts, known per se, arranged in the box and further for the mechanical locking, known per se, of the finger dial when the hand set is lying on the supports. As in this case the hand set, as

110

shown in Figs. 2 and 3, is horizontally situated above the finger dial the user of the apparatus must, of course, remove the hand set from the support before he can adjust the 5 finger dial to the correct number so that the mechanical locking of the finger dial may not be necessary.

It is supposed that the station works with 10 central battery and alternating current call signal and in this case the devices accommodated in the box are the following: An upright alternating current alarm W is mounted in the rear part of the box. This alarm consists of a two-armed permanent magnet 15 having a coil arranged between the arms. On one pole-piece of the coil an armature is horizontally mounted which covers the two arms of the permanent magnet. The clapper shaft fixed on the armature extends downward 20 in the rear rounded part of the box to a gong which is sounded when the armature oscillates. On the upper surface of the pedestal B a condenser K series-connected with the alarm and below said plate the commonly 25 used induction coil J are mounted.

On the condenser K two contact springs C are arranged adapted to come in contact with contacts of the number switch so that the electric contact of the number switch is effected 30 without the aid of a loose cord. At the right and left of the gong or of the induction coil sufficient space is available in the pedestal S for the connection of the connecting wires for the micro-telephone and for the outer conductors. In order to protect the elements in the pedestal against damaging from the outside the pedestal has a perforated bottom 35 plate B with rubber feet for supporting the desk telephone station.

40 The box D is fixed on the pedestal by means

of a bayonet joint. With this object in view flaps L are arranged on the upper surface of the pedestal and at convenient points on the inner surface of the box which come into engagement with one another when the box is 45 rotated after having been placed upon the pedestal. A screw screwed in from the lower side of the pedestal serves for preventing the accidental back rotation of the box.

The weight of the desk telephone station as 50 described is sufficient to ensure the stability at the rotating of the finger dial and to prevent tilting or displacement of the desk telephone when the hand set should be carelessly handled.

55 I claim:—

1. A telephone set comprising in combination, a base, all the apparatus required for the operation of the set as condenser, induction coil and alarm mounted on said base, a case 60 for this apparatus mounted on said base having an inclined top plate, a finger dial of standard construction about 3" of diameter mounted on the inclined top plate of said case, said base case and finger dial viewed from 65 above being all of approximately the same size.

2. A telephone set as specified in claim 1, comprising in combination with the base the case and the finger dial, said alarm mounted in the rear portion of said case in upright position, said condenser and said induction coil mounted in the front portion of said case, contacts on said condenser, counter contacts on 70 said finger dial so that these contacts and counter contacts touch each other when said case is mounted on said base.

75 In testimony whereof I affix my signature.

FRIEDRICH MERK.
